UNITED STATES PATENT OFFICE

1,934,570

IRONING MACHINE

John C. Suber, Deshler, Ohio

Application January 25, 1933. Serial No. 653,497

3 Claims. (Cl. 68—9)

The invention relates to an ironing machine and more especially to a table assembly for ironing machines.

The primary object of the invention is the provision of an assembly of this character wherein an ironing board or bed can be properly mounted in the ironing machine, it being possible to change the size of the board so that in the use of one size collars, handkerchiefs, napkins and other small articles may be ironed with smoothness and dispatch, while in the use of another size board the bosoms of shirts and the like can be ironed, the table assembly being of novel construction.

Another object of the invention is the provision of an assembly of this character wherein the same may be tensioned or untensioned and is susceptible of vertical adjustment to regulate the height of such board or top.

A further object of the invention is the provision of a table assembly of this character which is extremely simple in construction, thoroughly reliable and efficient in its operation when used in an ironing machine either of the hand or power type, strong, durable, interchangeable, and inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a side elevation of an ironing machine showing the table assembly constructed in accordance with the invention in use therewith.

Figure 2 is an end elevation partly in section.

Figure 3 is a top plan view of the table assembly, the same being partly broken away.

Figure 4 is a sectional view on the line 4—4 of Figure 3 looking in the direction of the arrows.

Figure 5 is an end elevation.

Figure 6 is a sectional view on the line 6—6 of Figure 4 looking in the direction of the arrows.

Figure 7 is a detail plan view of the mounting for the table assembly.

Figure 8 is a view similar to Figure 3 showing a slight modification.

Figure 9 is a sectional view on the line 9—9 of Figure 8 looking in the direction of the arrows.

Figure 10 is a plan view showing the board or the table assembly removed.

Figure 11 is an end elevation of the table assembly.

Figure 12 is a sectional view on the line 12—12 of Figure 9 looking in the direction of the arrows.

Similar reference characters indicate corresponding parts throughout the several views in the drawings.

Referring to the drawings in detail, particularly Figures 1 to 7 inclusive, A designates generally an ironing machine and includes the side frames 10 united with cross connecting pieces 11, the side frames being fitted with upper and lower bearings 11 and 12 respectively. The upper bearings have journaled therein the axle 13 for the ironing roll or mandrel 14, this being heated in any desired manner, while the lower bearings 12 have journaled therein the axle 15 for a feed drum 16. The axles 13 and 15 carry meshing gears 17 and 18 respectively, the gear 17 being the driving gear and the gear 18 the driven gear. The axle 13 has fitted therewith a hand crank 19 so that in this instance the ironing machine is of the hand operated type although it may be power driven.

Arranged between the side frames A above the drum 16 are spaced parallel guide tracks 20 for a table assembly. These tracks 20 have fitted therebetween intermediate and at the ends of the same rollers 21 for the table assembly and such rollers are journaled in suitable bearings therefor.

The table assembly comprises a base 22 of board-like character and this base is slidably fitted in the tracks 20 to be frictionally operated upon by the drum 16 at its under face so as to permit the travel of the table assembly longitudinally in the ironing machine during the operation thereof. Upon this base 22 is a mounting 23 including the spaced longitudinally and transversely aligned bearings 24 for rocking journals 25 of rocking bell crank-like levers 26, the arms 27 of which have pivoted at 28 thereto a substantially H-shaped connecting link 29 so that these levers turn in unison with each other. The cross piece 30 of the link 29 has centrally threaded therein the stem 21 of an adjusting member 32, its stem at the outer end thereof carrying a hand wheel 33 for the manual adjustment of the same. This stem 32 plays loosely through a center guide 34 formed on the mounting 23 in alignment with the threaded connection of the stem with the cross piece 30 of the link 29.

Superposed with respect to the mounting 23 is a saddle 35 having the depending legs 36 pivoted at 37 to the other arms 38 of the rocking bell crank levers 26. This saddle 35 has in opposite ends 39 thereof the center keyhole-shaped slots 110

40 for the detachable securing therein of the headed keeper lugs 41 carried by a table 42, the latter constituting the ironing bed and the same is so made up with a covering and pad (not shown) for ironing purposes. The detachable mounting of the table 42 upon the saddle 35 enables interchanging of small and large tables in the use of the table assembly in the ironing machine.

10 Surrounding the stem 31 of the adjusting member 32 is a coiled tensioning spring 43, one end being engaged against an adjustable collar 44 on the stem 31, which collar is threaded upon said stem, while the other end of the spring 43 rests against a slide collar 45 loose upon the stem 31 and contacting with an anti-friction bearing 46 interposed between the guide 34 and said collar 45 and about the stem 31, thus it being seen that by adjustment of the collar 44 the tension of the spring 43 can be regulated. This spring 43 under its tension holds the saddle normally in raised or elevated position and with the table 42 attached thereto the latter will be sustained under tension. This table 42 under the travel of the base 22 cooperates with the ironing roll 14 so that articles when placed upon the table will be ironed by said roll 14.

15 The table 42 under tension will maintain articles to be ironed thereon in close contact with the ironing roll 14 during the working of the ironing machine.

20 The base 22 at its rear end carries a hand grip 47, whereby it can be manually shifted in the ironing frame upon the tracks 20 for said base.

25 In Figures 8 to 12 inclusive of the drawings there is shown a slight modified form of table assembly, wherein the base 48 of board-like form has thereon the mounting 49 provided with the bearings 50 for the journals 51 of the rocking links 52 supporting the saddle 53 which is pivoted at 54 thereto. The cross piece 55 of the saddle 53 has centrally threaded therein the stem 56 of an adjusting member 57 provided with a hand wheel 58.

30 Resting upon the saddle 53 is the table 59, the same being formed with depending pins 60 which are slidably received in socketed posts 61 rising from and integral with the mounting 59. Thus it will be seen that the pins 60 slidably fitted in the posts 61 will permit the detachment of the table 59 so that different sizes of tables may be interchanged with the table assembly.

35 Adjustably threaded on the stem 56 is a collar 62 against which rests a coiled tensioning spring 63, the same also engaged against a collar 64 loose upon the stem and having its bearing against a guide 65 for the stem 56, the guide being a part of the mounting 49. The stem 56 carries a stop collar 66 which coacts with the

guide 65 to limit the throw of the saddle 53 in one direction, the spring 63 being for the purpose of tensioning the saddle and to normally hold it lifted whereby close contact of articles placed upon the table 59 with the ironing roll 14 may be had in the operation of the ironing machine for ironing purposes. The spring 63 can be regulated by the stem 56 for varying the tension of said spring in the use of the ironing table assembly in the ironing machine.

40 From the foregoing it is thought that the construction and manner of operation of the table assembly will be clearly understood and particularly in the use thereof in the ironing machine so a more extended explanation has been omitted for the sake of brevity.

45 What is claimed is:

1. An ironing machine table assembly comprising a movable bed, a mounting on said bed including spaced longitudinally and transversely aligned bearings, rockers movably connected with said bearings, a connecting link between said rockers, a table superposed relative to the connecting link and operated upon by the same, a guide on the mounting, an adjusting stem arranged in the guide and engaged with the connecting link, and tensioning means surrounding said stem for resiliently holding the table in adjusted position.

50 2. An ironing machine table assembly comprising a movable bed, a mounting on said bed including spaced longitudinally and transversely aligned bearings, rockers movably connected with said bearings, a connecting link between said rockers, a table superposed relative to the connecting link and operated upon by the same, a guide on the mounting, an adjusting stem arranged in the guide and engaged with the connecting link, tensioning means surrounding said stem for resiliently holding the table in adjusted position, and vertical guides for the table to cause the same to move perpendicularly.

55 3. An ironing machine table assembly comprising a movable bed, a mounting on said bed including spaced longitudinally and transversely aligned bearings, rockers movably connected with said bearings, a connecting link between said rockers, a table superposed relative to the connecting link and operated upon by the same, a guide on the mounting, an adjusting stem arranged in the guide and engaged with the connecting link, tensioning means surrounding said stem for resiliently holding the table in adjusted position, vertical guides for the table to cause the same to move perpendicularly, a track formed in the ironing machine for the bed, and means for varying the tension of the tensioning means.
